UNITED STATES PATENT OFFICE.

HARLOW F. CHAPIN, OF BROCKPORT, NEW YORK.

CAR-COUPING.

SPECIFICATION forming part of Letters Patent No. 437,900, dated October 7, 1890.

Application filed June 12, 1890. Serial No. 355,179. (No model.)

To all whom it may concern:

Be it known that I, HARLOW F. CHAPIN, a citizen of the United States, residing at Brockport, in the county of Monroe and State of New York, have invented a new and useful 5 Car-Coupling, of which the following is a specification.

My invention is an improvement in car-couplings; and it resides in the novel structure, 10 combination, and arrangement of parts, hereinafter fully described, and pointed out in the claims hereunto appended.

In the drawings illustrating my invention, forming a part of this specification, throughout which like letters of reference indicate corresponding parts, Figure 1 is a perspective view of the front and under sides of a car provided with my coupling. Fig. 2 is a vertical longitudinal section through the draw-head. Fig. 3 is a plan view of the draw-head.

In the drawings, A designates a car, having upon its under side the guides a, in which works the draw-bar B and the stop-plate a'. Between the stop-plate a' and the draw-head 25 B', encircling the draw-bar B, is a coiled spring C, and on the other side of the stop-plate a' abutting it, fastened to the end of the draw-bar B, is another coiled spring C', surrounding the draw-bar. These two springs 30 limit the movement of the draw-bar in either direction.

D is a rock-shaft extending across the end of the car below the draw-bar, having its ends provided with crank-handles d. Below the 35 draw-head B' the rock-shaft D has a curved arm d', which is used in a manner to be hereinafter described. At the side of the draw-head the rock-shaft D has another arm d'', which is connected by any suitable means— 40 such as a link-connection—with a rod d'', which extends to the top of the car, moving vertically in guides or staples.

The draw-head B' is provided with a vertical longitudinal slot b, in which is pivoted 45 the hook E. It also has a flaring mouth b', and in the rear of this mouth b', forming the end of the slot b, are the faces b² b³, beveled and curved, conforming to the front of the hook E, for a purpose to be described.

50 The hook E is pivoted on the shaft e, and is allowed a slight longitudinal movement

thereon by the slot e'. The head e² of the hook extends above the draw-head to provide means whereby the coupling may be performed by hand should any of the parts be 55 broken. The outer face of the hook E has its upper part e³ double beveled to correspond with the upper inner face b² of the mouth b', against which it rests. From a point e⁴ the outer face of the hook slopes in a curve e⁵ 60 downward and backward to the lower point e⁶ of the hook, and this curve e⁵ corresponds to the curve b³ of the mouth b'. Above the point e⁶ the hook is recessed, as at e⁷, to provide a space for the link to rest in. The 65 shoulder e⁸ limits its rearward movement. A flat spring e⁹ presses upon the upper face of the hook and keeps it in position. Two bolts e¹⁰ and e¹¹—one above and one below the hook E in the slot b—limit its movement. 70

The curved arm d' of the rock-shaft D engages the side of the recess e⁷, and when the rock-shaft D is operated by its handles d or by the rod d'' the hook is raised to release the coupling-link F. 75

In operation when the link F strikes the curved face e⁵ of the hook E the pin is thrust backward and upward, the slot e' allowing such movement until the link passes the lower point e⁶ of the hook, and, striking the shoulder e⁸, is caught in the recess e⁷ by the hook being pressed down by the spring e⁹. When the draft is brought to bear upon the coupling by means of the hook E, the same is carried forward, its upper bevel e³ resting against the 85 upper inner face of the mouth b', and its lower curve e⁵ resting against the lower inner face of the mouth. It will be seen that by this construction the greater the draft the firmer the link will be retained in place. It will also 90 be evident that by the form of the recess e⁷ and the spring e⁹ pressing the hook down the link F will be held in a horizontal position ready for coupling with another car.

Having thus described my invention, what 95 I claim as new, and desire to secure by Letters Patent, is—

1. In a car-coupling, the combination, with a draw-head provided with a vertical longitudinal opening and a flaring mouth, the rear 100 of which has an inner upper double beveled face, of a hook pivoted in the draw-head, and

having a slotted connection with its operating-shaft, the said hook having an outer face double beveled and provided with a rectangular recess e^7 on the under side of the hook, 5 and the uncoupling-arm d' , mounted on a rock-shaft and engaging the recess e^7 , substantially as and for the purpose described.

2. In a car-coupling, the combination, with a draw-head provided with a vertical longitudinal opening, of a hook pivoted in the draw-head and having a slotted connection 10 with its operating-shaft, and provided with a

rectangular recess e^7 on the under side of the hook, and the uncoupling-arm d' , mounted on a rock-shaft and engaging the recess e^7 , substantially as and for the purpose described. 15

In testimony that I claim the foregoing as my own I have hereto affixed my signature in presence of two witnesses.

HARLOW F. CHAPIN.
